RAILWAY TANK CAR

Hamilton Neil King Paton, Bellevue, and Ardell L. Scott,
Seattle, Wash., assignors, by direct and mesne assign-
ments, to Dorothy R. Paton, Bellevue, Wash.

Filed Jan. 14, 1963, Ser. No. 73,176

Term of patent 14 years

(Cl. D66—1)

FIGURE 1 is a top perspective view of a railway tank car, showing our new design;

FIGURE 2 is an elevational view of the side opposite that shown in FIGURE 1;

FIGURE 3 is an elevational view of the end opposite that shown in FIGURE 1;

FIGURE 4 is a transverse sectional view thereof taken along line 4—4 of FIGURE 2 on an enlarged scale;

FIGURE 5 is a transverse sectional view thereof taken along line 5—5 of FIGURE 2 on an enlarged scale.

We claim:

The ornamental design for a railway tank car, substantially as shown.
